ACCOUNTING AND FILING SYSTEM

Herbert Weston, New York, N. Y., assignor to
Visirecord, Inc., Long Island City, N. Y., a corporation of New York

Application June 3, 1950, Serial No. 165,967

4 Claims. (Cl. 129—16)

1

This invention relates to card indexes or card registers of the type in which the cards are arranged in horizontal echelon and in which the cards are arranged in groups separated from each other by dividers.

As is well known, in such filing systems, the lower edges of the cards are provided with slots adapted to coact with spacing members in the filing cabinet whereby each card is spaced laterally from the adjacent card to expose a portion of each card on which suitable identifying entries are made. The upper edge of each card may also be provided with suitable marking which is normally covered by the adjacent card but which is exposed when the adjacent card is removed from the cabinet thereby giving a "card out" indication or signal.

In such systems, groups of cards are generally separated from adjacent groups by dividers and the groups may further be divided into subgroups by intermediate dividers. The present invention is directed to the construction of the divider. To protect the upper edge of the cards from wear, the dividers generally extend upwardly beyond the tops of the cards. If the dividers are made of cardboard, sheet metal or any of the usual materials, this results in a decrease in visibility and is, therefore, a disadvantage.

In the patent to Bosse No. 2,192,178, granted March 5, 1940, there is disclosed and claimed a divider construction in which the upper edge portion is transparent. This permits the divider to extend beyond the edges of the cards to protect them and at the same time permits index markings and the like to be seen through the transparent portion of the divider.

The present invention constitutes an improvement over the transparent divider of the Bosse patent. Dividers are generally provided with end rails of greater thickness than the sheet material of which the body portion of the divider is formed. These end rails are, therefore, in contact with each other and the cards occupy the space between the sheet material or body of the divider extending between the end rails at opposite sides. In the Bosse construction the transparent upper portion of the divider extends upwardly in the same plane as the body portion which provides an open space at the top.

In the present invention the body portion of the divider is preferably made of an opaque material, such as sheet metal or the like. The upper edge is formed of a transparent plastic and extends upwardly a slight distance in the plane of the body portion of the divider and then

2

curves rearwardly. The "card out" indications on the upper edges of the cards are visible through the straight lower portion of the upper edge of the divider and other indicators, such as index members, mounted on the intermediate dividers, are visible through the curved portion of the upper edge of the divider. This curved portion may be shaped, in cross section, to produce magnification to facilitate reading of the indexes and the like.

The shape of the upper edge of the divider not only provides for magnification and better reading of the index members but it also substantially covers the otherwise open space and thereby renders the filing cabinet member dust-proof. It eliminates to a great extent dropping of paper clips, cigarette ashes and the like into the file.

As a further feature of the invention, the rear face of the transparent portion of the divider may be flat and may be provided with channels at its upper and lower edges to receive index tabs or cards. As the index tab is slidable in these channels, they may be positioned at any desired point transversely of the divider.

If the end rails are made of a plastic material which is relatively noninflammable, such as Tenite II (a product of the Tennessee Eastman Co.), and a metal cabinet is employed, the cards are substantially protected from fire. In case of fire, the upper curved portion of the divider melts slightly and covers the space between the divider and the next divider, thereby cutting off supply of air to this space and preventing the cards from burning.

In the accompanying drawings I have shown several embodiments of the invention. In this showing:

Fig. 1 is a front elevation of a divider and an assembled group of registry cards, the cards being indicated in dotted lines;

Fig. 2 is a vertical, sectional view on line 2—2 of Fig. 1;

Fig. 3 is a similar view taken near one edge of the divider and showing a method of supporting an index member;

Fig. 4 is a perspective view of a number of dividers, groups of cards, and intermediate dividers assembled showing index members on the intermediate dividers;

Fig. 5 is a detailed, sectional view showing the end rail construction; and

Fig. 6 is a perspective view on an enlarged scale illustrating the assembly of the end rail and the body portion of the divider, and showing a modification of the divider.

Referring to the drawings, the reference nu-

meral 1 designates generally the bottom of a filing cabinet or case in which the cards are arranged. This case is provided with a plurality of aligning or positioning members 2 extending from the front to the rear of the case. These members are adapted to be received in slots 3 in the bottom of the cards and in filing, the cards are positioned in echelon with the edge of each card C spaced a distance from the edge of the adjacent card as indicated at 5. On the upper edge of each card inwardly from the inclined edge 6 a distance equal to the normal spacing between two cards, a signal or indication 7 is provided which, when visible, indicates that one card has been removed. Thus, in Fig. 1 it will be noted that the space between the edges of the third and fourth cards from the left is twice as great as that between the rest of the cards indicating a missing card. This exposes the "card out" signal 7 on the fourth card whereas in connection with the other cards, such signal is covered by the adjacent card.

The divider which constitutes the main feature of the present invention is represented generally by the reference numeral 10 and consists of a body portion 11, a transparent upper edge portion 12 and end rails 13. The body portion may be made of any suitable material, such as fire-proof board, metal or the like. It is thus generally opaque. To provide for the proper visibility and at the same time protect the upper edges of the cards, the transparent strip 12 is secured to the upper edge of the body portion. As shown, the body portion may be offset as at 14 and the strip 12 may be secured in front of this offset portion substantially flush with the front surface of the body portion. It may be secured to the body portion in any suitable manner as by rivets 15. The strip 12 includes a portion 16 extending upwardly in the same plane as the body portion of the divider and a portion 17 which is curved rearwardly toward the next divider. This portion may be shaped as indicated in Figs. 2, 3, and 6 of the drawings to form a magnifying lens.

The end rails 13 may be of suitable form but are generally of greater width or thickness than the sheet material from which the body of the divider is made, and when a number of them are placed in a cabinet, form a substantially solid or continuous side wall as shown in Fig. 4 of the drawings, the groups of cards being arranged in the spaces between the body portions of the two adjacent dividers, as shown in Fig. 2 of the drawings. Where large groups of cards are filed, intermediate dividers 18 are arranged between sub groups and these intermediate dividers have suitable index members 19 on their upper edges which are visible through the curved portion 17 of the upper edge of the transparent portion of the divider.

Adjacent the edges of a divider, as shown in Fig. 3 of the drawings, an index member 20 may be positioned. This may be accomplished by placing a second curved strip 21 of the same material of which the strip 12 is formed in the rear of the strip 12 forming a spaced between the two strips into which the index member 20 may be slipped.

The body portion of the divider may be secured to the end rail in any suitable manner. In the drawing I have shown the end rail substantially channel shaped having a front leg 22 and rear leg 23. If the body portion of the divider is made of metal, such as aluminum, each side edge may be bent upon itself, as shown at 24. The leg 22 may be molded with a space 25 into which the edge

24 is inserted and after this edge of the body of the divider has been inserted, the material forming the end rail may be heated to soften it and mold it over the end of the section 24.

It will be apparent from the foregoing description that the transparent upper edge member 12 not only provides visibility but also provides magnification through the curved portion 17 to increase the visibility of the index members 19 on the intermediate dividers the "card out" signals or other information on the upper edges of the cards, and the main index numbers 20. It also protects the interior of the cabinet from accidental dropping of paper clips, pins and the like, into the cabinet. In case of fire, as this strip softens, it moves downwardly toward the tops of the cards and forms a substantially closed top. With a file cabinet built of metal and preferably with a double walled bottom and with the side edges closed by the end rails, which may also be made of non-inflammable plastic materials, cards are thus protected against destruction by fire. Any of the available plastics which are transparent and will soften at elevated temperatures may be used.

In the form of the invention shown in Fig. 6 of the drawing, the transparent strip 12 comprises a portion 26 extending upwardly in the plane of the body portion of the divider as heretofore described, and a portion 27 that extends rearwardly. The front face of the portion 27 may be shaped to function as a magnifying means. The rear face 28 is arranged in a single plane. At its upper and lower edges, the rear face is provided with channels or guides 29 to receive the edge of an index member. The index member may be slipped into position with its upper and lower edges in these channels. As the channels extend the full length of the divider, or entirely across the filing cabinet, two or more index members mounted on dividers in the cabinet may be positioned laterally so that one in front of another does not conceal it from view.

This application is a continuation-in-part of my application Serial No. 126,733, filed November 12, 1949, now abandoned.

I claim:

1. In a card registry, a plurality of dividers, the dividers comprising end rails of appreciable thickness and sheets connecting the end rails, the end rails when assembled forming substantially solid side walls and forming spaces between the sheets for the reception of cards, the upper portions of the sheets forming the body of the dividers being of transparent material, said transparent portions extending upwardly and rearwardly and being of thermoplastic material, said transparent portions in their upward and rearward direction having a length at least substantially as great as the width of the spaces between the sheets in a direction normal to the surfaces of the sheets, and a length in said direction sufficient that when said transparent portions are heated above their softening point they will sag and substantially bridge the upper portion of the space between the sheets.

2. A card registry as defined in claim 1 in which the rearwardly-extending section of the transparent upper portion is shaped to form a magnifying means.

3. A card registry as defined in claim 1 in which a second strip of transparent material similarly shaped to the transparent upper portion of the divider is secured to the body portion of the divider and is spaced from the transparent upper

portion to form a space to receive an index number.

4. A card registry as defined in claim 1 in which the rear face of the rearwardly-extending part of the transparent upper portion is flat and is provided with a longitudinally-extending channel to receive an index member.
